HYPODERMIC SYRINGE

Arthur E. Smith, Los Angeles, Calif.

Application January 17, 1948, Serial No. 2,900

9 Claims. (Cl. 123—220)

1

This invention relates to a hypodermic syringe. The general object of the invention is to provide an improved hypodermic syringe of the disposable type in which the parts are of such a nature that they can be readily manufactured and assembled.

Another object of the invention is to provide a novel front member for a syringe.

A further object of the invention is to provide a hypodermic syringe including novel means for preventing premature or accidental movement of the parts of the syringe.

Other objects and advantages of the invention will be apparent from the following description taken in connection with the accompanying drawings, wherein:

Fig. 1 is a side elevation showing my improved syringe;

Fig. 2 is an enlarged, central, sectional view showing the syringe before it is prepared for use, and

Fig. 3 is a view similar to Fig. 2, showing the syringe after it has been prepared for use.

Referring to the drawing by reference characters, I have shown my invention as embodied in a hypodermic syringe which is indicated generally at 10'. As shown the syringe is of the disposable type and includes an ampule or barrel 11' and a plunger 12'. The barrel may be made of tubular material such as glass and has a rubber stopper 13' in one end. The stopper includes an axial recess 14' and an axial depression 15' with a diaphragm 16' between the recess and the depression. The stopper includes a flange 17'.

The plunger 12' includes an inner end which is recessed at 60 to receive the body of a piston stopper 61 which has peripheral beads 62 thereon at the inner end thereof. The stopper 61 is preferably made of rubber and has axial recesses 25' and 26' separated by a diaphragm 27'.

At its forward end the plunger has a front member which is shaped to provide a finger engaging flange 30' and has a bore 31' which receives the body of a front end closure 32' which is preferably made of rubber and includes a rounded front end tip 33'. The closure 32' includes an inner axial recess 34' separated by a diaphragm 35' from an axial recess 36' which communicates with another axial recess 37'. The recess 37' communicates with a recess 38', the inner wall of the recess 38' being beveled as at 39'. A hole 40' affords communication between the outer recess 38' and the end of the tip 33'.

The plunger 12' has an axial bore 50' in which I arrange a hypodermic needle 51'. This needle has a sharpened tip 51" disposed normally adjacent the diaphragm 27' and is adapted to pierce the diaphragm to place the needle in communication with the contents of the ampule when the needle is moved axially along the plunger.

2

The needle includes a fixed hub 52' which has a head 53' thereon, normally arranged in the recess 38'. The head 53' is shown as beveled to correspond to the bevel 39' of the recess. The hub includes a finger engaging head portion 55' by means of which the needle may be moved so that the head 53' passes into the recess 37', at which time the diaphragm 27' will have been pierced by the tip 51" of the needle.

I provide a cap member 65 which serves to protect the hypodermic needle during shipment and prior to use. This cap member has a bore 66 which receives the needle, and the end 67 of the cap member engages the hub 55' when in normal position. To prevent premature piercing of the diaphragm 27' by the inner end of the needle, I provide a seal member, indicated generally at 68 and which may consist of a strip of adhesive tape 69 to which a block 70 is secured. This block 70 may be of plastic material and fits between the end 71 of the plunger tip and the shoulder 72 at the inner end of the hub 55' and thus prevents axial inward movement of the hub. The free end 73 of the seal engages the cap member 65 and includes a finger engaging releasing tab 74. The finger engaging tab 74 may be made by folding the end of the strip upon itself.

The seal member 68 further may include a block 75 which engages the flange 30' and the end 76 of the ampule 11', and normally prevents collapsing movement of the ampule and plunger.

In use the syringe is prepared so that it is in the condition shown in Fig. 1. The operator then grasps the tab 74 of the seal and strips away the seal, first removing the block 70 and thus allowing the cap member 65 to be pushed and thereby push the needle inwardly until the hub 53' has passed into the recess 37', whereupon the cap 65 may be removed. Removal of the block 75 by further moving the seal 68 permits the plunger to move into the ampule.

Applicant's present application, Serial No. 2,900, filed January 17, 1948, relates to a syringe wherein there is a barrel having a front member, a recess and with a needle extending through the front member and recess and having a protuberant portion engageable in the recess and with the needle adapted to be advanced to its seated position by means of a protective cap carried upon the needle.

In applicant's copending application Serial No. 1,551, filed January 10, 1948, now Patent No. 2,538,391, dated January 16, 1951, the claim is directed to the piston stopper which is hollow and has pierceable front and rear closures therein, the front closure acting as a plunger and both closures being pierceable by the needle of a filling apparatus.

60 In applicant's copending application Serial No.

548, filed January 5, 1948, now Patent No. 2,538,390, dated January 16, 1951, the claim is directed to the outer barrel with a front closure therein and the claim includes the sliding barrel forming ampule within the outer barrel and with the piston closure in the sliding barrel at its front end. The claim also includes the piston plunger within the sliding barrel and having a piston head thereon.

From the foregoing description it will be apparent that I have invented a syringe which may be economically manufactured and which is highly efficient for its intended use.

Having thus described my invention, I claim:

1. A syringe including a barrel and a plunger movable in said barrel, said plunger having a front member thereon, said front member having an elongated recess, and a needle extending through said front member, said needle having a protuberance thereon disposed in said recess and adapted to move inwardly in the recess when the needle is moved inwardly, releasable means normally preventing inward movement of the needle, and means on the front member to hold the protuberance when in its inward position in the recess.
2. A syringe including a barrel and a plunger movable in said barrel, said plunger having a front member thereon, said front member having an elongated recess, and a needle extending through said front member, said needle having a protuberance thereon disposed in said recess and adapted to move inwardly in the recess when the needle is moved inwardly, and releasable means normally preventing inward movement of the protuberance in the recess.
3. A syringe including a barrel and a plunger movable in said barrel, said plunger having a front member thereon, said front member having an elongated recess, and a needle extending through said front member, said needle having a protuberance thereon disposed in said recess and adapted to move inwardly in the recess when the needle is moved inwardly, a cap member about the needle, means on the needle engaging the cap member to cause the needle to move with the cap member, and means on the front member to hold the protuberance when in its inward position in the recess.
4. A syringe including a barrel and a plunger movable in said barrel, said plunger having a front member thereon, said front member having an elongated recess, and a needle extending through said front member, said needle having a protuberance thereon disposed in said recess and adapted to move inwardly in the recess when the needle is moved inwardly, a cap member about the needle, means on the needle engaging the cap member to cause the needle to move with the cap member, and releasable means normally preventing movement of the cap member.

5. A syringe including an outer ampule member and an inner plunger member slidable in the outer member, a front closure on one of said members, said front closure having a recess therein, a needle extending through said closure and having an enlargement thereon normally disposed in the recess, one of said members having a diaphragm normally closing communication from said one member to the needle, the inner end of said needle being positioned to pierce said

diaphragm when the needle is moved, and releasable means normally preventing movement of the plunger in the ampule.

6. A syringe including an outer ampule member and an inner plunger member slidable in the outer member, a front closure on one of said members, said front closure having an axial recess therein, a needle extending through said closure and having an enlargement thereon normally disposed in the recess, said front closure having a second axial recess communicating with and disposed inwardly from the first axial recess; one of said members having a diaphragm normally closing communication from said one member to the needle, the inner end of said needle being positioned to pierce said diaphragm when the needle is moved so that the enlargement is disposed in the second axial recess, and means normally preventing movement of the needle.
- 10 7. A syringe including a barrel and a plunger movable in said barrel, said plunger having a front member thereon, a needle extending into said front member, said needle having a hub thereon, said needle being adapted to move inwardly in the front member when the needle hub is moved inwardly, and displaceable means engaging the front member and the hub and normally preventing inward movement of the needle.
- 15 8. A syringe including a barrel and a plunger movable in said barrel, said plunger having a pierceable front member thereon, a needle having an inner end portion extending into said front member, said needle having a hub thereon, said needle being adapted to move inwardly in the front member to pierce the front member when the needle hub is moved inwardly, said needle having an outer end portion, and a cap member surrounding the needle outer end portion and engaging the hub, said cap member being shiftable with the hub to cause movement of the hub and needle to force the needle through the front member when the cap member is moved.
- 20 9. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 25 10. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 30 11. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 35 12. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 40 13. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 45 14. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 50 15. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
- 55 16. A syringe including a barrel and a plunger movable in said barrel, said plunger having a front member thereon, a needle extending into said front member, said needle having a hub thereon, said needle being adapted to move inwardly in the front member to pierce the front member when the needle hub is moved inwardly, a cap member about the needle, the cap member engaging the hub to cause the hub and needle to move with the cap member, and displaceable means disposed between the front member and the hub to prevent forward movement of the hub.
